Nathan I. Fleischer,
By Arthur H. Edward,
Attorney.

UNITED STATES PATENT OFFICE

NATHAN I. FLEISCHER, OF CINCINNATI, OHIO, ASSIGNOR TO I. FLEISCHER & SONS, OF CINCINNATI, OHIO, A FIRM COMPOSED OF NATHAN I. FLEISCHER AND JACOB I. FLEISCHER

PROTECTIVE COVER

Application filed July 21, 1931. Serial No. 552,160.

My invention relates to protective covers, for example, of the type designed to cover the upper portion of a garment as suspended on a hanger, particularly when on display for sale.

The principal object of my invention is to provide a simple and inexpensive protective cover of the type mentioned, which while it protects the garment or other article from dust and soil during handling and display, does not interfere with the inspection of the article by the prospective purchaser. To this end my new protective cover is constructed of cellophane, or other similar cellulose product which is fully transparent, the same being provided with an edging or binding which amply protects the cellophane from tearing or ripping at the edges.

A further object of my invention is to provide for a cellophane or other similar cellulose protective cover, a binding so attached to the edges thereof that no stitching or similar means are required for securing together the binding and the main body of the protector.

A still further object of my invention is to provide for a cellophane or other cellulose product protector of the type mentioned, an adhesive binding so constructed as to be attachable to the edges of the protector throughout its curves and deviations from straight alignment, without the necessity of crimping, buckling or folding the binding at the curves or other turns; in other words, to provide a binding which throughout the entire attachment will rest smoothly against the body of the protective cover.

Further objects of my invention will appear from the following detailed description thereof.

In the drawing:

Figure 1 is an elevation of a protective cover constructed in accordance with this invention.

Figure 2 is a section on line 2-2 of Figure 1.

Figure 3 is an elevation showing the construction and attachment of the edging or binding material.

Figure 4 is an elevation illustrating the use of the protective cover.

The numeral 1 indicates an envelope or body portion of my new protective cover, the same being constructed of cellophane or other cellulose product; said envelope is constructed preferably of two sheets 2 and 3 of the desired material, said sheets being of substantially registering shape, the sheet 2, however, having its upper portion cut away as shown at 4 so as to provide an opening 5 at the central upper portion of the protector. The sheets 2 and 3 are assembled by means of an edging or binding 6 which extends from the lower side corners of the sheets upwardly around the curved conformation of the sheets securing the same together. Where the alignment of the sheets deviates at the cut away portion 4, the binding 6 follows sheet 3. A similar binding 7 is secured along the edge of 4 of the sheet 2, and the ends thereof are suitably merged with the binding 6. Similar binding tapes 8 and 9 are placed around the lower edge of the sheets. Where the binding 6 at the upper central portion of the protector is applied only to the sheet 3, it covers both faces around the edge so as fully to protect the same. The bindings 7, 8 and 9 also cover both faces of the material along the edges as clearly shown in Figure 2. The bindings 6, 7, 8 and 9 are preferably constructed of tape which is cut diagonally or on a bias as clearly shown in Figure 3 of the drawing, one side of the tape being provided with an adhesive by means of which it may be secured to the body of the protector.

In Figure 4 I have illustrated the use of my new protector. A dress 10, or other similar garment, with the protector over the upper portion of same, is placed on a hanger 11 by means of which it may be suspended on a rack or bar for display in the usual manner. By reason of the fact that the main body of the protective cover is constructed of transparent material the garment may be inspected without the removal of the protector. As constructed with the adhesive bindings 6, 7, 8 and 9 all edges of the cellophane material are fully bound and

protected against tearing, and there is, furthermore, no likelihood of the binding itself being ripped or torn from the body, as is the case where the binding is stitched thereto.

5 in such cases the stitching itself providing points of rupture in the cellophane which readily increase in size and soon destroy the protector.

Furthermore, it will be noted that by reason of the peculiar construction of the binding material, it may be placed around the entire contour of the protector without at any point buckling, crimping or providing other inequalities which in addition to being 15 unsightly prevent the proper packing and handling of the devices in quantities.

It will thus be seen that in the device above described and illustrated in the drawing I have provided a protective cover of great 20 utility, as well as great simplicity and neatness in construction, and which may be adapted not only for garments as shown in the drawing and above described, but which by reason of its construction may be made 25 available for many other articles of merchandise merely by giving same the proper shape and dimensions.

Having thus fully described my invention, what I claim as new and desire to secure by 30 Letters Patent is:

1. A protective cover comprising two sheets of transparent material shaped so as to register along their edges except at the upper central portion, where one of said 35 sheets is cut lower than the other, an adhesive tape secured over the registering side edges of said sheets to assemble same, and continuing as a binding overlapping the two surfaces of the higher edge at the nonregistering 40 portions of the sheets, a second adhesive tape overlapping the two surfaces of the lower edge at said nonregistering portions, and separate adhesive tapes each overlapping the two surfaces of the lower edge of one of said 45 sheets.

2. A protective cover comprising two sheets of transparent material shaped so as to register along their edges except at the upper central portion, where one of said 50 sheets is cut lower than the other, a bias cut adhesive tape secured over the registering side edges of said sheets to assemble same, and continuing as a binder overlapping the two surfaces of the higher edge at the nonregistering 55 portions of the sheets, a second adhesive tape overlapping the two surfaces of the lower edge at said nonregistering portions, and separate adhesive tapes each overlapping the two surfaces of the lower edge 60 of one of said sheets.

NATHAN I. FLEISCHER.
